UNITED STATES PATENT OFFICE.

SIMON W. WARDWELL, OF PROVIDENCE, RHODE ISLAND.

METHOD OF MANUFACTURING LACINGS.

1,172,328.

Specification of Letters Patent.

Patented Feb. 22, 1916.

Application filed July 15, 1911. Serial No. 638,734.

To all whom it may concern:

Be it known that I, SIMON W. WARDWELL, a citizen of the United States, residing at Providence, in the county of Providence and State of Rhode Island, have invented certain new and useful Improvements in Methods of Manufacturing Lacings, of which the following is a specification.

My invention relates to the manufacture of lacings for use with articles of apparel such as shoes, corsets, etc., or for other purposes, and consists particularly of improvements in the method of forming the tips at the ends of the lacing which are provided to facilitate threading it through the eyelets.

The object of my improvement is to dispense with the use of the unsightly and easily destroyed metal tips now generally employed; and, further, to provide for manufacturing the tip as an integral part of the lacing, fashioned in the same machine.

To this end my new method of manufacture contemplates the braiding, weaving or otherwise fabricating of a continuous length of material having reduced tip portions formed at suitable intervals along its length, and adapted to be cut apart to produce the separate lacings.

The novel process of manufacture is fully described in the following specification, illustrated by the accompanying drawings, in which:

Figure 1 is a view of a length of braided fabric fashioned with reduced tip portions of round section and illustrating the method of cutting the tips apart; Fig. 2, an enlarged detail view of the tip end of my improved lacing showing the character of the braid; Fig. 3, a sectional view of the fabric taken on the line A—A of Fig. 3, looking in the direction indicated by the arrow *a*; Fig. 4, a similar view taken on the line B—B of Fig. 3, looking in the direction indicated by the arrow *b*.

Referring to Fig. 1 of the drawings, the body portion of the lacing, designated *L*, is preferably formed of tubular fabric, braided, woven or otherwise fabricated, in any well known manner to give the desired pattern, and adapted to be pressed into a substantially flat tape or strap. At certain in-

tervals along its length the strip of tubular fabric *L* is reduced in diameter and the strands of thread, yarn, fibers, or other attenuated material from which it is fabricated, are drawn together and compacted into substantially solid, round portions *T* as illustrated more clearly in Fig. 4. These round portions *T* occur at the proper distance apart to give the required length to the separate lacings, determinate upon the use for which they are intended and, obviously, the length of the lacings can be varied at will. It will be obvious, also, that the reduced tip portions *T* are made of such length that when cut apart midway of the points where they merge into the tubular portions *L*, or on the lines *x*—*x*, Fig. 1, the severed ends will form the tips *t*, *t*, as illustrated at the bottom of Fig. 1. It will be evident that the length of the tips can also be varied according to any particular requirement or style by regulating the length of the round portion *T* of the braid.

As before stated, the main portion of the lacing is preferably of tubular fabric pressed into the form illustrated most clearly at *L*, Fig. 3, and this portion tapers down into the round portion shown in magnified section at *T*, Fig. 4. The tubular fabric *L* is usually braided, with the strands passing over and under each other in any well known recticular pattern such as "basket" or "plain" braid, so called, and the threads are relatively loosely meshed. Where the braid merges into the tip portions *T*, however, the strands are drawn as tight as possible so that they will be compacted solidly into a hard, cylindrical cord which possesses considerable inherent stiffness and rigidity. This compacting and solidifying of the structure of the fabric may be accomplished by increasing the tension on the yarns and accelerating the rate of feed of the material through the braiding machine, so that the strands are laid more closely and with a longer wrap around the fabric. In addition to changing the character of the braid in this manner I have also found it advisable to vary its pattern, as now described, to provide for producing a denser structure in the tip portions. To this end I prefer to carry

out my invention by employing a braiding machine similar to that shown and described in my Patent No. 1,081,474, Dec. 16, 1913, which is capable of producing different patterns in one continuous strip of fabric.

Referring to Fig. 2, it will be noted that the main portion L of the lacing is shown having a pattern generally known as "basket" braid, while the tip portion T has a different pattern as now described. In the portion L of the braid the yarns cross each other at substantially right angles, passing over and under each other in pairs, while in the tip portion T the yarns are shown as crossing each other at very much greater angles so that they lie more nearly parallel to edge of the fabric. In other words, the yarns in the tip portions T have a greater lead or pitch and therefore are compacted more closely and firmly to reduce the size of the fabric and give the desired hard, rope-like structure to the tip of the lacing. To prevent the ends of the tips from fraying or raveling after the lacings are cut apart I prefer to coat them with a waterproof covering of shellac, varnish, glue, cement, enamel or other suitable compound which will amalgamate the structure of the fabric and also add to its stiffness. I have found in practice that shellac is well adapted to this purpose since it hardens quickly and is impervious to heat, cold and moisture.

It will be seen from the above that my improved process of manufacture produces a lacing having terminal tips formed integral with the main portion and presenting a particularly neat and finished appearance. By dispensing with the usual applied tips my improved lacing is made more durable, since metal tips are liable to become detached in use and are frequently crushed and bent out of shape from being stepped upon. Furthermore, it has been found well nigh impossible to enamel or color metal tips with a permanent coating so that they soon become worn and shabby looking.

Heretofore in manufacturing lacings it has been necessary to first braid the fabric and then either supply or form the tips by some other process. With my improved process the complete lacing can be produced in the same machine, the tips being fashioned as part of the braiding operation and the operation of cutting the lacings apart and dipping their ends being accomplished by suitable devices operating in conjunction with the braiding mechanism. In this way I not only greatly cheapen the cost of manufacture but I also improve the appearance and finish of the article.

It will be understood that I do not herein claim the improved lacing itself, the same being the subject of a separate application filed concurrently herewith. It is further

to be understood that I do not herein limit myself to any particular style or character of fabric or braid in producing my improved lacing, nor do I limit myself to the exact procedure of manufacture described above; but

What I do claim is:

1. The herein described process of manufacturing lacings consisting in intermeshing fibrous strands to form a continuous tubular strip of fabric and changing at predetermined intervals the pattern to compact the strands forming portions of reduced cross section adapted to serve as tips. 75

2. The herein described process of manufacturing lacings consisting in intermeshing fibrous strands to form a continuous tubular strip of fabric and changing at predetermined intervals the pattern to compact the strands forming portions of reduced cross section adapted to serve as tips, and severing said strip in said reduced portions. 80

3. The herein described process of manufacturing lacings consisting in intermeshing fibrous strands with relative looseness to 90 form a continuous tubular strip and changing the intermeshing operation at intervals to bring the strands more closely together to form a hard round cord of less diameter than the tubular portion adapted to serve 95 as a tip.

4. The herein described process of manufacturing lacings consisting in intermeshing fibrous strands with relative looseness to 100 form a continuous tubular strip and changing the intermeshing operation at intervals to bring the strands more closely together to form a hard round cord of less diameter than the tubular portion adapted to serve 105 as a tip, and severing said cord portion between its ends.

5. The herein described process of manufacturing lacings consisting in intermeshing fibrous strands to form a continuous strip of fabric having tubular portions substantially equal in length to the length required for the lacings and changing the intermeshing operation at intervals to compact the strands more closely together to form a hard, round, cord-like portion between each two adjacent tubular portions, and severing said cord portion between its ends to adapt the same to serve as tips for the main portion of the lacing. 110 115

6. A new process for the manufacture of 120 lacings consisting of braiding a strip of tubular fabric with the strands relatively loosely meshed; and then changing the braiding operation to braid the strands under greater tension to lay them more nearly parallel with the edge of the fabric to form a hard, round cord of less diameter than the tubular portion and adapted to serve as a tip for the end of the lacing. 125

7. A new process for the manufacture of 130

lacings consisting of braiding a strip of tubular fabric with the strands loosely intermeshed to cross each other at substantially right angles; and then changing the 5 character of the braid to mesh the strands under greater tension, the strands crossing each other at greater angles so as to lie more nearly parallel to the length of the braid

and forming a substantially solid, round cord adapted to serve as a tip for the lacing. 10

In testimony whereof I affix my signature in presence of two witnesses.

SIMON W. WARDWELL.
